UNITED STATES PATENT OFFICE.

WILLIAM W. WATSON, OF JAMESTOWN, NEW YORK.

METAL WINDOW SCREEN FOR RAILWAY CARS.

1,408,849.

Specification of Letters Patent. Patented Mar. 7, 1922.

Application filed May 21, 1921. Serial No. 471,466.

To all whom it may concern:

Be it known that I, WILLIAM W. WATSON, a citizen of the United States, residing at the city of Jamestown, in the county of Chautauqua and State of New York, have invented certain new and useful Improvements in Metal Window Screens for Railway Cars, of which the following, taken in connection with the accompanying drawings, is a specification.

The invention relates to sheet metal window screens as adapted to railway cars and similar uses; and the object of the improvement is to provide a strong and durable sheet metal screen frame with locking bolts in the opposite upper corners and frame sides, which bolts are connected to one another and through the tubular screen sides to an opening in the lower screen side so as to be operable to withdraw said bolts from the locking notches in the guide strips on the window frame when in the raised position in the frame of the car above the visible window frame, in which raised position said bolt cannot be manually withdrawn, but must be actuated by means of a withdrawal hook which draws the screen downward to screen the window opening; and the invention consists in the novel features and combinations hereinafter set forth and claimed.

In the drawings, Figure 1 is an elevation of a car window with the car frame in section showing the improved window screen in the elevated position with the withdrawal hook in position for withdrawing the bolts from their locking engagement in the notches in the guide strips, and for drawing the window screen downward to screen the window opening when the sash is raised. Fig. 2 is a horizontal crosswise sectional view at line 2—2 in Fig. 8; and Fig. 3 is a vertical sectional view at line 3—3 in Fig. 8, the central portions of the frame being broken away to show large sectional views of the frame sides. Fig. 4 is a perspective view of the strengthened end of the tape showing the opening therethrough to receive the pivot pin. Fig. 5 is a perspective view of the channel-shaped lever piece in the lower frame side as arranged for engagement by a withdrawal hook. Figs. 6 and 7 show lengthwise sectional and end elevations of the combination bolt barrel and pin guideway. Fig. 8 is an elevation of the screen frame, portions of the screen frame

being shown in section to show the construction and arrangement of the same as to the tubular frame sides and the flexible tape and pulley connection between the turn or crank plate in the upper frame side and the withdrawal lever in the lower frame side for actuating said turn or crank plate to withdraw the locking bolts and lower the screen. Fig. 9 is a crosswise sectional view of the frame at line 9—9 in Fig. 8 showing the preferred construction of said frame sides. Fig. 10 is a lengthwise sectional view of an upper corner of the tubular frame showing the spring bolt, link, turn plate, and tape and pulley connection for the withdrawal of the spring bolts and the openings in the frame side. Fig. 11 is a sectional view of one of the struck-up bolt barrels showing the spring bolt within the same; and Fig. 12 is an end elevation of the same. Fig. 13 is a perspective view of the insert strip for holding the lateral side springs in working position within the frame side.

Like characters of reference refer to corresponding parts in the several views.

The numeral 15 designates the tubular sheet metal frame side which is cut and bent from the flat sheet metal strip by means of suitable dies so as to form the lengthwise groove 16 along the inner edges of said frame side.

The numeral 17 designates the upper frame side or top rail which is preferably formed of one or more strips of sheet metal shaped so as to provide said lengthwise groove 16 which opens sidewise along the inner edge, and the narrow lengthwise groove 18 which also opens sidewise along the outer edge, both of said grooves enlarging inwardly. The inner groove 16 enlarges inwardly to receive the spline or holding strip 19 for attaching the screen fabric 20 within the groove 16. The outer groove 18 enlarges inwardly to receive and retain therein the weather stripping 21 which fits within the groove 18 and extends beyond the plane of the rail or frame side.

The top rail or upper tubular frame side 17 is preferably formed of a plurality of sheet metal strips, the contacting edge portions of which are pressed together and bent into the lengthwise channel grooves 16 and 18 along the inner and outer edges of the same, the edges of said strips being so arranged as to narrow the mouths of each of said grooves 16 and 18, the thickness of the

inturned sheet metal edges so that said grooves may be said to enlarge inwardly to hold the spline 19 and the weather striping 21. The contacting edges of said sheet metal strips are preferably welded or soldered or otherwise attached so that they cannot turn or weave upon one another, thereby giving rigidity to the frame.

The lower cross rail or tubular frame side 10 22 is preferably made of two sheet metal strips 23 and 24 in somewhat the same form as the upper frame side or cross rail 17, the exceptions being that the groove 16 is made slightly different, the strip 24 being bent 15 at an inclined angle 25 to prevent the use of the lowering hook 26 upon the screen or frame side in lowering the same, and the lengthwise groove 27 for the weather strip 28 is preferably formed on the outer side 20 of the lower edge of the rail 22 so that said groove 27 opens downward and the weather strip 28 may be pressed downward onto the window sill to make a tight joint between said window sill and the screen frame.

25 The corners of the screen frame are preferably mitered and united by soldering or welding, though they may be united by any other suitable means. The opposite corners of the upper frame side are provided with the spring bolts 29 and 30 in barrels 31 and 32 to engage in the notches 33 of the guide strips 34 on the window frame at each side.

The opposite lateral edges of the screen frame have the grooves 35 and 36 to receive 35 the guide strips 34. The groove 35 is formed in the solid tubular sheet metal lateral frame side 37 as shown in section at the left in Fig. 2. The groove 36 is formed in the channel-shaped insert 38, which fits in the lengthwise groove 39 in the opposite lateral frame side 40, which insert 38 carries therein a strip insert 41, preferably of wood, having the pairs of notches 42 to receive therein the angularly bent ends of the leaf springs 43. 40 A pair of inwardly projecting guide pins 44 are provided, one in each end of the channel-shaped insert 38, which pins 44 engage in guideways 45 and 46 provided in the tubular frame side to thereby hold said channel-shaped insert 38 in vertical alinement as it 45 adjusts outwardly and inwardly in moving up and down the guide strips 34 on the window frame, or when inserting said screen into the window frame, always holding said springs 43 in working position as they press against the bottom of the groove 39. The wood strip insert 41 braces and strengthens the entire lateral frame side as well as holds the springs 43 in working position, giving 50 added stiffness and strength to the resilient frame side so that it is instantly adjustable to small variances as to the distance between the guide strips 34.

60 The spring bolt 29 has the barrel 31 preferably struck up from sheet metal with the

sidewise extension 47 which forms the guideway 46 for the upper guide pin 44 for the channel shaped insert 40 to hold said insert in vertical alinement. Said sidewise extension is preferably of sufficient length to form 70 an oblong guideway 46 so as to permit the vertical sidewise movement of the pin 44 in its relation to its companion pin 44' in guideway 45 at the opposite end of the insert 38, since absolute accuracy is unnecessary in the 75 movement or placing of these pins as to their vertical movement. The necessary part is to hold said pins 44 in vertical alinement so that the insert 40 does not weave or move sidewise and the screen frame will travel 80 upward and downward with ease and accuracy.

The barrel 32 for the locking bolt 30 is preferably struck up in the tubular form from the sheet metal, the inner ends of each 85 of the barrels 31 and 32 being closed slightly to hold the springs on the reduced portion of the locking bolts 29 and 30, and permit the link connection to said bolts. The spring locking bolts 29 and 30 in their barrels 31 90 and 32 are connected to a turn or crank plate 48 by links 49 and 50 and pivot or wrist pins 51 and 52 in take-up slots 53 and 54. The slots 53 and 54 permit the use of 95 manually actuatable levers 55 and 56 which are connected to the bolts 29 and 30 to manually withdraw the same when the screen frame is accessible as when in the lowered position.

It is apparent, however, that when in the 100 raised position in the frame 57 of the car side as shown in Fig. 1 with said screen frame pushed upward between the window sash 58, it is necessary to use the lowering hook 26 to withdraw the spring bolts 29 and 105 30 from the locking notches 33 and draw the screen downward until it can be manually placed in the lowered position to screen the window opening as shown in dotted outline in Fig. 1. In order to accomplish this withdrawal of the bolts 29 and 110 30 when the screen frame is in the raised position, a tape 59, preferably of steel or some equally bendable metal, is attached to the turn or crank plate 48 and pulleys 60 and 115 61 are provided within the hollow tubular frame side at the upper and lower lateral corners thereof so that said tape 59 can be carried over said pulleys to a centrally placed preferably channel-shaped lever 120 piece 62 pivotally attached at one end over a slot 65 in the lower frame side in such a manner that the downward turning of the channel-shaped lever piece 62 through the slot 65, as shown in dotted outline in Fig. 8, 125 draws upon the tape 59 and moves the turn plate 48 to simultaneously withdraw the bolts 29 and 30 from the holding notches in the guide strips 28.

The channel-shaped lever piece 62 which 130

is engaged by the lowering hook 26 serves also to draw the screen frame downward until it can be manually grasped and lowered, thereby serving a double purpose to withdraw the bolts 29 and 30 and to lower the screen frame. The channel-shaped lever piece 62 is pivotally attached in the lower corner at 63, while the tape 59 is pivotally attached at 64 at the upper corner. As stated, the lever piece 62 is pivotally attached over the slotted opening 65 in the under edge of the lower frame side and has the slotted opening 66 therein for the insertion of the lowering hook 26 over a cross bar 67 as shown in Figs. 5 and 8, so that said lever piece 62 may be drawn downward as shown in dotted outline in lowering the screen frame as hereinbefore described. As soon as the lowering hook is removed and the spring bolts 29 and 30 are permitted to spring outward into the lower locking notches in the guide strips on the window frame, said lever piece 62 will be drawn upward into the closed position in the lower frame side.

When the screen frame is in the lowered or accessible position, it is necessary to manually actuate the spring locking bolts 29 and 30. For this purpose the manual actuating levers 55 and 56 are provided which extend down through the lower edges of the upper frame side, and are connected to said spring bolts 29 and 30, their actuating links being pivotally attached within said upper frame side. In order also to assemble the spring bolts, turn plate and connective link mechanism with the manual actuating levers and tape within the upper frame side 17, a cover 69 is provided for said frame side 17 which fits closely over the same as shown in Figs. 3 and 10. This arrangement permits the provision of openings 70, 71 and 72 in said top rail 17 opposite the points of assemblage of said parts. The cover 69 is channel-shaped and fits closely over said top rail 17 so it can be sprung onto the same and give a pleasing finish, yet permits its quick removal for access to the connective joints to assemble or repair the same.

The cover 69 is shown in Fig. 1 with the locking mechanism in dotted outline within the top rail beneath said cover. Said cover 69 is not shown in Fig. 8 since said top rail is in section, the side upon which said cover 69 would be placed being removed. The exact channel shape and the relation of said cover in fitting over the parts is clearly shown in Fig. 3 in cross section.

The channel strip insert 38 is held within the frame side and against displacement by means of a screw 73 and a closed end 74 on the lower end of said channel strip insert 38. The upper end is held in place by means of a cotter pin 75 through the inner end of the 65 guide pin 44, which cotter pin does not per-

mit the escape of said pin 44 from its guide-way.

It is apparent that a chain or wire cord might be used in place of the tape 59 without departing from my invention. The flexible steel tape, however, has been found to serve the purpose so well that it is preferred since it is easy of adjustment and works smoothly over flat edged pulleys 60 and 61, from which pulleys it cannot slip 75 sidewise because of the inner walls of the tubular frame sides. Said tape is preferably strengthened at its point of pivotal attachment by a trap 76 with out-turned edges 77 as shown in Fig. 4, so as not to break in 80 bending at this point.

What is claimed as new is:

1. In a window screen lock, in combination with a frame having locking bolts at the upper corners thereof, a central member pivoted between its ends to the top rail of the screen, links connected to the bolts at one end and having their opposite ends formed with longitudinal slots, pins connected to the respective ends of the central member and extending into the slots, guides at the top and at the bottom of one end of the frame, a cord connected to one end of said central member and trained over the guides and having its opposite end extending along the lower rail of the frame, a channeled shaped element pivoted within the lower rail and connected to the cord and having its closed side facing downwardly and formed with slots defining a cross bar 100 to engage a hook, and a hand lever connected to each link and extending below the upper rail to move the slots of the links relative to the pins of the central member and to the exclusion of the latter to thereby 105 actuate the bolts.

2. In a window screen lock, in combination with a frame having locking bolts at the upper corners thereof, a central member pivoted between its ends to the top rail of the screen, links connected to the bolts at one end and having their opposite ends pivotally connected to the respective ends of the central member, guides at the upper and lower corners of the frame, a cord connected to said member and trained over the guides, and a pivoted member carried by the lower side of the frame and connected to the cord for operating the latter and thereby the 115 bolts.

3. In a window screen lock, in combination with a frame having locking bolts at the upper corners thereof, a central member pivoted between its ends to the top rail of the screen, links connected to the bolts at one 125 end and having their opposite ends pivotally connected to the respective ends of the central member, guides at the upper and lower corners of the frame, a cord connected to said member and trained over the guides, 130

and a pivoted channeled shaped member carried by the lower side of the frame and having its closed side facing downwardly and being slotted to form a cross-bar, said 5 last named member being connected to the cord for operating the latter and thereby the bolts.

4. In a window screen lock, in combination with a tubular screen frame having 10 locking bolts at its upper corners, means to actuate the bolts carried by the lower rail of the screen, means connected to said actuating means and to the bolts to operate the latter by and from said actuating means, a 15 hand lever for actuating each bolt independent of said actuating means, and means whereby to allow of operation of the hand levers to the exclusion of movement of said actuating means.

20 5. In a window screen lock, in combination with a screen frame having locking

bolts at its upper corners, means to actuate the bolts carried by the lower rail of the frame, and means located within the frame and connecting said bolts and the actuating 25 means for operating the bolts from the actuating means.

6. In a window screen lock, in combination with a screen frame having locking bolts at its upper corners, means to actuate 30 the bolts arranged on and carried by the lower rail of the frame, and means connecting said bolts and the actuating means for operating the bolts from the actuating means.

35 In testimony whereof I have affixed my signature in the presence of two witnesses,

WILLIAM W. WATSON.
